UNITED STATES PATENT OFFICE.

SAMUEL TULLY WILLSON, OF BROOKLYN, NEW YORK.

STOVE-TOP.

1,032,575.

Specification of Letters Patent. Patented July 16, 1912.

Application filed July 7, 1910. Serial No. 570,869.

To all whom it may concern:

Be it known that I, SAMUEL TULLY WILLSON, a citizen of the United States, residing in Brooklyn, in the county of Kings, in the 5 State of New York, have invented certain new and useful Improved Stove-Tops; and I do hereby declare the following to be a full, clear, and exact description of the invention, such as will enable others skilled 10 in the art to which it appertains to make and use the same.

This invention relates to stove tops and especially to that class of stoves used by confectioners, or candy makers, or in other 15 arts where large oval bottom vessels of various sizes, are required to be heated on the same stove.

The object of the invention is to provide means of supporting the vessel in such a 20 manner that a small oval, or as usually described round bottomed vessel, will be approximately the same distance from the heat supplying medium as a large vessel.

A further object of the invention is to 25 provide a stove top, the parts of which will have greater strength, due to their shape, than has heretofore been customary.

A further object of the invention is to 30 provide a stove top, the parts of which due to their shape, can better withstand, without breaking, expansion and contraction due to heating and cooling.

With these and other objects in view, the invention comprises certain novel constructions, combinations and arrangements of parts, as will be hereinafter more fully described and claimed.

In the drawings:—Figure 1 is a top view disclosing a form of this invention as it 40 appears with all the parts assembled. Fig. 2 is a vertical sectional view of the top, showing it combined with a gas burner and furnace body as it may be arranged for a confectioner.

45 Similar letters refer to similar parts in both views.

Concentric ring stove tops, are usually constructed of cast material with separate rings set one within the other and their tops flushed and flat; and rings of the size 50 required to fit the vessel are used. In the improved construction, these rings which are made to fit together in a similar way, are dished as shown in Fig. 2 rings being numbered 2 3 4 and 5 so that when a small 55 vessel indicated by K_1 is placed in the ring which it fits, the bottom of the vessel will be approximately the same distance from the heat supplying medium as a large vessel 60 #1; also a vessel K_2 of intermediate size, would fit in ring #3 making its bottom also the same distance from the heating medium, while if the rings were all flat, K_1 would be considerably farther from the heating medium than K_2 and would therefore show 65 considerable less economy of fuel.

Having thus described my invention, what I claim is:—

1. In a stove or furnace top, removable 70 dished concentric rings arranged to support various sized vessels with their bottoms in approximately the same location.

2. In a furnace top or top portion, removable dished or concaved concentric rings, 75 each outer ring supporting the next inner ring, and each ring dished sufficiently so that the kettle which fits into it will be a fixed distance from the heat supplying medium.

3. A stove top comprising a plurality of removable ring sections, said sections gradually decreasing in diameter from the uppermost to the lowermost section, each section converging downward and adapted to 85 support the section next below.

S. TULLY WILLSON.
